UNITED STATES PATENT OFFICE.

ALEXANDER KEITH, OF TORONTO, CANADA.

METHOD OF MIXING ACETYLENE GAS AND AIR FOR HEATING PURPOSES.

No. 823,538.

Specification of Letters Patent.

Patented June 19, 1906.

Application filed April 4, 1903. Serial No. 151,143.

To all whom it may concern:

Be it known that I, ALEXANDER KEITH, of the city of Toronto, in the county of York, in the Province of Ontario, Canada, have invented certain new and useful Improvements in Methods of Mixing Acetylene Gas and Air for Heating Purposes, of which the following is a specification.

My invention relates to an improved method of mixing acetylene gas and air for heating purposes, and more especially for burning in connection with an ordinary mantle-burner to heat the mantle to incandescence.

In connection with the ordinary tip of an open-flame burner acetylene gas tends to cause obstruction in the tip by reason of deposits thereon, and with the mantle-burner, from this tendency to deposit and from other causes, it has been heretofore impracticable to burn acetylene gas in such burners.

The object of my invention is to overcome this difficulty, and by means of my invention I am able to burn this gas in a mantle-burner without obstruction or smoke and with an extraordinary illuminating power. Heretofore attempt has been made to burn acetylene gas in a mantle-burner by a direct discharge of such gas unmixed through a small orifice small enough to prevent back-firing, but with openings opposite such orifice to the atmosphere to allow the air to be drawn in by the force of the jet of gas; but this fails to perfectly mix the gas, and as the amount of the air taken in depends upon the force of the jet of gas that amount varies with the force of discharge of the gas and so materially as to render the result uncertain and the method impracticable.

It has been attempted to remedy the difficulty of deposit in ordinary-tip open-flame burners by forcing currents of air against the exterior surface of the tip, and thereby lifting or removing the combustion-point from immediate contact with the tip; but this is not applicable to mantle-burners, however much air it may supply to the acetylene gas. It is important in the use of this highly-illuminating gas in the mantle-burner, for the production of a steady uniform light without clogging or injury to the mantle, that the gas should be mixed with air and that this mixture should be thorough and complete and uniform in proportion, and, further, it is important that the mixing should be automatic in the apparatus. To meet these require-

ments and conditions, I have devised and practically applied to use my invention, which consists in a method of using acetylene gas for producing light from any suitable source in connection with a mantle-burner by mixing said gas with atmospheric air or any suitable equivalent thereof in proper proportions prior to the supply of the mixture to the burner.

In order that the apparatus may be automatic and that the proportions may be maintained under varying pressure of the gas, I carry out my invention preferably by means of an "automatic" mixer, by which I mean that the mixer is operated by the pressure of the gas and maintains the relative proportions and at the same time supplies the mixture to the burner under suitable pressure.

This invention I have illustrated in the accompanying drawings, in which

Figure 1 illustrates the apparatus in automatic form. Fig. 2 shows the mixing apparatus partly in side elevation and partly in section.

In the diagram of Fig. 1, S indicates any suitable source of supply of the acetylene gas, from which a pipe P leads to the mixing apparatus, (indicated at M,) and from this mixing apparatus a pipe Q leads to branch pipes, such as 1, which directly connect with the ordinary mantle-burners.

The special form of mixing apparatus shown in Fig. 2 had been devised by me with the particular object of being operated by the gas-pressure and of producing and maintaining the uniform mixture of the air and gas prior to supplying it to the burners and, further, with the object of rendering the apparatus simple in construction and not liable to derangement; but it will be understood that I do not limit myself to this special form of apparatus, nor do I herein claim this special form, this being the subject of another application.

Referring now to Fig. 2, B and B' represent gas-holders provided with vertical moving bells 3 and water seal. Mounted upon these bells, but not communicating therewith, are expandible or bellows extensions C C', the upper ends of which are connected with a fixed plate 4, the construction being such that the extension is collapsed, as shown at C', when the bell 3 is in its raised position, and the bellows are extended, as shown at C, when the bell is down in the holder. These bellows are adapted to hold air and act as

pumps receiving air through automatic valves 17 and 18 from the atmosphere and forcing it through valves 15 and 16 into bellows D, as hereinafter more fully explained. Gas is supplied to the holders from the pipe P through branches 5 and 6 and an interposed three-way cock 7. These branches extend upward into the holders, as shown, and discharge therein. The valve is controlled by 15 to a hollow arm 8, centrally connected at its stem and provided with a weight 9, adapted to shift from end to end of the arm. This connection is through spurs, by means of which and the shifting of the weight the final movement of the valve is rendered certain and prompt. The two ends of the arm are connected, respectively, with the upper ends of the bells by chains 10 and 11, the arrangement being such that when one end of the lever 8 is down the valve opens into the branch pipe on that side and is closed on the other. Under continued pressure, therefore, from the pipe P the holders will be filled automatically and alternately, the arm of the valve 20 being controlled through the chains by the alternate rising and falling of the bells, and thus the holders are alternately filled and extended. The branch pipes 5 and 6 are supplied with suitable automatic valves at their 25 ends. Alternate discharge of gas from these holders is effected through branch pipes 12 13, connected to a central pipe 14, discharging through a suitable automatic valve into the bellows D. The ends of these branch pipes within the holders are provided also with suitable automatic valves. The bellows D are mounted upon the plate 4, to which its bottom is fixed, and the bellows expand upwardly when supplied with the mixture of 30 gas and air. The gas is supplied, as explained, through the pipe 14. The air is supplied alternately from the bellows C' through the valves 15 16, opening upwardly from the bellows. These bellows receive the air from 35 the atmosphere through the valves 17 and 18, and it will readily appear from an inspection of Fig. 2 that when the bell is rising on one side and compressing the bellows it is discharging the air contained therein into the bellows D, 40 while the downward movement of the bell on the other side expands the bellows and takes in air through its proper valve; also, that the reverse operation is the same. It will also be evident that while the gas is entering through 45 the pipe 6—for example, on one side—it is by this expansive force compressing the bellows on that side, and thus forcing air into the bellows D, while at the same time the gas is also

passing through the pipes 13 and 14 into the bellows D. Meanwhile the bellows C are taking in air. The proportions of air and gas are determined by the relative dimensions of bellows D and C. The bells are returned to their depressed condition by means of weights 18' acting on the bellows on each side, to 50 which they are attached. The bellows D are returned by the weight 19. The flow of gas is controlled by means of a valve F, on the stem of which is an arm 20, provided with a weight 21 and connected to a lever 22, pivoted at 24 and having a weight resting at 23 on top of the bellows D. The arrangement is such that when the bellows D are expanded with the mixture it will lift the lever 22 and through its connections turn the valve F and 55 shut off the gas, while the collapse of the bellows D will reverse the valve.

The proportions of the parts are such, preferably, as to mix the air and gas in equal volumes, as this has been found in my process to 60 give good results; but I do not limit myself to these proportions either in the apparatus or process.

The pipe Q leads from the bellows D to the branches which carry the burners. 65

The mixture of the air and gas is complete and intimate when it is delivered to the mantle-burner without causing deposits upon the tip or injury to the mantle, and with this mixture so delivered the mantle-lamp can be 70 burned uniformly and continuously with an exceedingly brilliant light and with no more difficulty than is experienced with ordinary illuminating gas.

The point at which the mixture of gas and air takes place is not material, provided that it be thoroughly mixed and delivered in the pipe before reaching the discharge-orifice. 75

What I claim as my invention is—

The method herein described of mixing 80 acetylene gas and air for heating purposes, the same consisting in continuously mixing with said gas, air at a pressure in excess of atmospheric pressure in approximately equal proportions to produce a solely calorific flame by 85 utilizing the pressure of the gas between the generator and burner, which produces a mixture of necessarily a lower pressure than the pressure of the gas, and burning the mixture within a mantle of incandescent material, 90 substantially as described.

ALEXANDER KEITH.
